UNITED STATES PATENT OFFICE

JAMES R. PRICE, OF PROVIDENCE, RHODE ISLAND, ASSIGNOR TO THE ALVIN CORPORATION, OF PROVIDENCE, RHODE ISLAND

DESIGN FOR A SPOON OR SIMILAR ARTICLE

Application filed May 25, 1933. Serial No. 48,209. Term of patent 14 years.

To all whom it may concern:

Be it known that I, JAMES R. PRICE, a citizen of the United States, residing at Providence, in the county of Providence and State of Rhode Island, have invented a new, original, and ornamental Design for a Spoon or Similar Article, of which the following is a specification, reference being had to the accompanying drawing, forming part thereof.

I claim:

The ornamental design for a spoon or similar article, as shown.

In testimony whereof I have signed my name to this specification.

JAMES R. PRICE.
